CLAIM

The ornamental design for a shower panel as shown and described.

DESCRIPTION

FIG. 1 is a perspective view of a shower panel, showing the first embodiment of my new design;

FIG. 2 is another perspective view thereof;

FIG. 3 is a front elevational view thereof;

FIG. 4 is a rear elevational view thereof;

FIG. 5 is a partial enlarged view of FIG. 1;

FIG. 6 is a partial enlarged view of FIG. 1;

FIG. 7 is a perspective view of a shower panel, showing the second embodiment of my new design;

FIG. 8 is another perspective view thereof;

FIG. 9 is a front elevational view thereof;

FIG. 10 is a rear elevational view thereof;

FIG. 11 is a partial enlarged view of FIG. 7;

FIG. 12 is a partial enlarged view of FIG. 7;

FIG. 13 is a partial enlarged view of FIG. 7;

FIG. 14 is a perspective view of a shower panel, showing the third embodiment of my new design;

FIG. 15 is another perspective view thereof;

FIG. 16 is a front elevational view thereof;

FIG. 17 is a rear elevational view thereof;

FIG. 18 is a partial enlarged view of FIG. 14;

FIG. 19 is a partial enlarged view of FIG. 14; and,

FIG. 20 is a partial enlarged view of FIG. 14.

The broken lines define the bounds of the enlargements and do not form part of the claimed design.
